MOLDED HEADREST

**Sylvan Yavner, 412 Bradford Ave.,
Norfolk, Va. 23505**

Filed Nov. 26, 1969, Ser. No. 20,280

Term of patent 14 years

Int. Cl. D6—02

U.S. CL. D15—8

FIG. 5

FIG. 6

FIG. 7

FIG. 8

FIG. 1 is a plan view of the molded headrest embodying my new design;

FIG. 2 is a front elevational view thereof;

FIG. 3 is a sectional view thereof taken along the line 3—3 of FIG. 1;

FIG. 4 is a side elevational view thereof;

FIG. 5 is a view of the under surface thereof;

FIG. 6 is a rear elevational view thereof taken along the line 6—6 of FIG. 4;

FIG. 7 is a sectional view thereof taken along the line 7—7 of FIG. 1; and

FIG. 8 is a perspective view thereof.

I claim:

The ornamental design for a molded headrest, as shown and described.
